COMPARTMENTED COVER FOR A TRAY

Steve Cyr and Mark Whelan, Chippewa Falls, Wis., assignors to Standard Oil Company, Chicago, Ill.

Filed June 12, 1970, Ser. No. 23,462

Term of patent 14 years

Int. Cl. D9—07

U.S. Cl. D9—254

F/G. 1

FIG. 3

FIG. 1 is a perspective view of the interior of a compartmented cover for a tray showing our new design;

FIG. 2 is a plan view of the interior of a compartmented cover for a tray;

FIG. 3 is a plan view of the exterior of a compartmented cover for a tray;

FIG. 4 is a front elevational view of a compartmented cover for a tray;

FIG. 5 is a rear elevational view of a compartmented cover for a tray;

FIG. 6 is a side elevational view of one end of a compartmented cover for a tray, the opposite end being the mirror image of FIG. 6.

We claim:

The ornamental design for a compartmented cover for a tray, as shown and described.
